US00D543549S

(12) **United States Design Patent** (10) **Patent No.:** **US D543,549 S**
Monney et al. (45) **Date of Patent:** **** May 29, 2007**

(54) **COMPUTER KEYBOARD**

(75) Inventors: **Patrick Monney**, Mex (CH); **Laurence Massey**, Dublin (IE); **Alexis Richard**, Cully (CH); **Alain Tabasso**, Esertines (CH); **Wim Vanheertum**, Divonne les Baines (FR)

(73) Assignee: **Logitech Europe S.A.** (CH)

(**) Term: **14 Years**

(21) Appl. No.: **29/261,788**

(22) Filed: **Jun. 19, 2006**

(51) **LOC (8) Cl.** **14-02**

(52) **U.S. Cl.** **D14/455**

(58) **Field of Classification Search** ..... D14/320, D14/331, 333, 338, 388, 391-9, 432, 454-7; D18/1, 2, 12.2, 52; 178/17 A, 17 C; 235/145 A, 235/145 R, 146; 341/22, 23; 345/156, 168-9; 400/485-9, 472, 496

See application file for complete search history.

(57) **CLAIM**

The ornamental design for computer keyboard, as shown and described.

DESCRIPTION

FIG. 1 is a perspective view of a computer keyboard showing our new design;

FIG. 2 is a right elevational view thereof;

FIG. 3 is a left elevational view thereof;

FIG. 4 is a top plan view thereof;

FIG. 5 is a front elevational view thereof;

FIG. 6 is a bottom plan view thereof; and,

FIG. 7 is a rear elevational view thereof.

Phantom lining, where utilized, is for illustrative purposes only, and is not intended to limit the claimed component design to the features shown in phantom.

1 Claim, 3 Drawing Sheets
